UNITED STATES PATENT OFFICE.

JACOB C. LARSEN, OF COLUMBUS, OHIO, ASSIGNOR TO THE BUCKEYE STEEL CASTINGS COMPANY, OF COLUMBUS, OHIO.

CAR-TRUCK SIDE FRAME AND JOURNAL-BOX CONSTRUCTION.

Application filed November 14, 1923. Serial No. 674,671.

To all whom it may concern:

Be it known that I, JACOB C. LARSEN, a citizen of the United States, and resident of Columbus, in the county of Franklin and 5 State of Ohio, have invented certain new and useful Improvements in Car-Truck Side Frame and Journal-Box Constructions; and I do hereby declare the following to be a full, clear, and exact description of the invention, such as will enable others skilled in the art to which it appertains to make and use the same.

This invention relates to means for connecting journal boxes and side frames of car trucks and has for its objects the provision of means whereby the accidental separation of the side frame and the journal box will be prevented, the provision of a fastening device permanently mounted in the side 10 frame so that it cannot be removed and lost, the provision of a construction which will permit the journal box to be quickly connected or disconnected when wheel changes or other repairs to the truck are necessary, 15 and the provision of a construction which will permit the journal box to adjust itself to the position of the axle. These stated objects and other objects which will hereinafter incidentally appear are attained in such a 20 construction as is illustrated in the accompanying drawings, and the invention resides in certain novel features which will be particularly pointed out in the appended 25 claims.

30 In the drawings, Figure 1 is a longitudinal section of an end portion of a truck side frame with a journal box in section connected therewith; Figure 2 is a side view of a journal box with a portion of the side frame in section on the line 2—2 of Fig. 1; Figure 3 is an end view of the side frame; Figure 4 is a horizontal section on the line 4—4 of Figure 1, and Figure 5 is a side view of the journal box.

40 The side frame 1 is provided at its ends with pedestal jaws 2, 3, which are provided in their inner opposed sides with vertical grooves 4 opening through the jaws at their lower ends. The journal box 5 is fitted between the jaws and is provided on its sides with lugs 6 which are adapted to enter the grooves 4 as the side frame is moved vertically downward over the journal box, the relative descending movement of the side

frame being limited by the lugs coming into contact with the closed upper ends 7 of the grooves, and the arch 8 between the jaws coming to rest upon the top 9 of the box. The box is provided with spaced transverse gibbs 10, 11 extending across its top and between which the arch of the side frame is received. The inner gib 10 extends only across the top of box but the outer gib 11 extends down the sides of the box in spaced relation to the lugs 6 so that it forms a 55 guide for the side frame while the latter is being assembled with the box. The distance between the gibbs is slightly greater than the width of the side frame so that while the endwise accidental removal of the 60 journal box from the side frame is prevented, a limited shifting of the box is permitted so that it will readily accommodate 65 itself to the position of the car axle.

In the outer jaw 3 of the side frame is 70 formed an obliquely disposed recess or chamber 12 which opens downwardly into the groove 4 and from the top of which a 75 relatively reduced bore or opening 13 extends through the upper web or body portion of the jaw. In the upper side of the web is a notch 14 which receives and retains the upper end of a locking pin 15 fitted 80 slidably through the opening 13 and having a head 16 at its lower end playing in the 85 recess or chamber 12 and normally projecting from said chamber into and across the groove 4. In assembling the parts, the pin is inserted upwardly through the opening 13 and its upper end is then bent, as shown at 90 17, to engage the notch 14. Complete withdrawal and loss of the locking pin is thus 95 prevented.

As the side frame moves downwardly into position over the journal box the upper 95 beveled side of the lug 6 will impinge against the outer angularly disposed head 16 of the locking pin and will push the pin upwardly until its head clears the lug whereupon the pin will return by gravity so 100 that the head will engage under the lug and lock the box to the side frame.

If, for any reason, it becomes necessary to remove a pair of wheels, the locking pin of each box is first moved upward in the 105 angularly disposed chamber 12, until it clears the lug 6 of the box; the side frames are then raised until the top 9 of the box

clears the pedestal jaw 3 of the frame, after which the pair of wheels with axle and journal boxes may be rolled out sufficiently to allow space for the new pair of wheels between the truck and the old wheels.

After transferring the journal boxes and parts to the new axle, the complete unit of wheels, axle, and journal boxes are rolled into position and the side frames lowered.

10 It will be noted that the disassembling and assembling of the side frames and the journal boxes is accomplished by one uninterrupted vertical movement of the side frame.

Having fully described my invention what 15 I claim as new and desire to secure by Letters-Patent, is:—

1. A truck side frame having jaws with vertical grooves opening through their lower ends, a journal box spanned by the 20 jaws, lugs on the journal box receivable in the vertical grooves, and a locking element mounted in one jaw to project into the groove therein and engage under the lug on the journal box.

25 2. A truck side frame having jaws with vertical grooves opening through their lower ends, a journal box spanned by the jaws, lugs on the journal box receivable in the grooves, and a locking device permanently mounted in one jaw and engageable under the lug on the journal box.

3. A truck side frame having jaws with vertical grooves opening through their lower ends, a journal box spanned by the 35 jaws and provided on its sides with lugs receivable in the grooves, and a gravitating locking pin mounted in one jaw and project-

ing into the groove therein to retain the journal box in engagement with the jaw.

4. A truck side frame having jaws with vertical grooves therein, one of the jaws having an obliquely disposed opening therethrough, a relatively enlarged chamber at the lower end of the opening communicating with the groove in said jaw, and a lateral notch at the upper end of the opening, a locking pin fitted slidably through the opening and having a stop member at its upper end to engage said notch, a head at the lower end of said pin playing in said chamber and normally projecting into the communicating groove, and a journal box spanned by the jaws and provided on its sides with lugs received in the grooves, the lug received in one groove being retained 55 therein by the head of the locking pin.

5. A truck side frame having spaced jaws with vertical inner opposed faces and having vertical grooves in said faces opening through the lower ends of the same, and a journal box provided with lugs on its sides to enter said grooves and be housed by the back and side walls thereof, the box being further provided with gibs between which the side frame is received, one of said gibs 60 extending down the sides of the box in spaced relation to the lugs.

In testimony whereof, I have signed this specification in the presence of two subscribing witnesses.

JACOB C. LARSEN.
